[57] CLAIM

The ornamental design for a support stand for athletic training device, as shown and described.

DESCRIPTION

FIG. 1 is a front right side perspective view of the support stand of the present invention showing my new design, the broken line depiction of the ball and tether being for illustrative purposes only and forming no part of my new design;

FIG. 2 is a front elevational view thereof; and,
FIG. 3 is a right side elevational view thereof.

The surfaces or portions of the article not shown in the drawing or described in the specification form no part of the claimed design.
